PAGE 3

Fig. 4.

Fig. 1 is a front perspective view of a vacuum cleaner embodying our new design.

Fig. 2 is a rear perspective view thereof.

Fig. 3 is an enlarged front elevational view thereof with the upper portion of the vacuum cleaner omitted.

Fig. 4 is an enlarged top plan view thereof with the upper portion of the vacuum cleaner omitted.

Fig. 5 is an enlarged side elevational view thereof with the upper portion of the vacuum cleaner omitted.

Fig. 6 is an enlarged perspective view of the hand grip portion thereof.

We claim:

The ornamental design for a vacuum cleaner or similar article, substantially as shown.
